MULTIPLE TAMPING MACHINE

Robert C. Melanson, Winthrop, Mass.

Application September 27, 1956, Serial No. 612,381

8 Claims. (Cl. 94—49)

This invention relates to machines and equipment used in construction; and in particular a machine having multiple tamping bars actuated by camshafts extended through horizontally disposed slots in ends of the bars and operatively connected to the bars with sliding blocks or bearings, with a roller positioned ahead of the bars, another roller positioned to follow the bars, and with power means for actuating the camshafts for vertically reciprocating the tamping bars.

The purpose of this invention is to provide a machine having a plurality of vertically reciprocating tamping bars, in which the bars are particularly adapted for compacting and leveling hot or cold bituminous concrete, and for reducing the concrete to the required density at compaction.

Various types of tamping machines have been provided and although such machines are satisfactory for many purposes they are not suitable for relatively large slabs of bituminous concrete and other comparatively soft materials for which high-speed tamping is required. With this thought in mind, this invention contemplates a plurality of elongated transversely disposed bars with ends of the bars mounted on off-set sections of camshafts whereby with the camshafts rotating at comparatively high speeds, such as nine hundred r.p.m. a beating action is obtained and a slab with a smooth upper surface is obtained.

The object of this invention is, therefore, to provide a tamping machine having a plurality of vertically slideable bars reciprocating at high speed and mounted to travel over a body of comparatively loose material such as bituminous concrete where increased densities and high degrees of compaction are required.

Another object of the invention is to provide a tamping machine in which the machine is readily maneuverable.

A further object of the invention is to provide a relatively high speed tamping machine in which the machine is of a simple and economical construction.

With these and other objects and advantages in view the invention embodies a framework having parallel camshafts positioned in opposite sides thereof, transversely disposed tamping bars having slots extending inwardly from the ends positioned whereby the camshafts extend through the slots, a motor positioned above the bars for driving the camshafts, ground engaging rollers adjustably mounted on the frame for regulating the elevation of lower surfaces of the tamping bars and a handle with a tank thereon extended from the frame and positioned whereby fluid from the tank is drained by gravity to the surfaces of the rollers.

Other features and advantages of the invention will appear from the following description taken in connection with the drawings, wherein:

Figure 1 is a side elevational view of the improved tamping machine.

Figure 2 is a front elevational view of the machine;

2

Figure 3 is a longitudinal section through the machine taken on line 3—3 of Figure 2 illustrating the relative positions of the tamping bars.

Figure 4 is a cross section through the machine taken on line 4—4 of Figure 1 illustrating the design of the tamping bars.

Figure 5 is a perspective view of the machine with the parts assembled showing the device in an operative position.

10 Referring now to the drawing wherein like reference characters denote corresponding parts the improved tamping machine of this invention includes parallel tamping bars 10 slidably mounted between channel bars 11 and 12 with camshafts 13 and 14 extended through horizontally disposed slots 15 and 16 in ends of the bars. The ends of the camshafts are rotatably mounted in bearings formed with upper sections 17 and lower sections 18 and the sections 17 and 18 are provided with V-shaped upper and lower edges whereby the bearings are retained in position laterally and are free to slide longitudinally of the bars by cam elements 19 and 20 in the slots. The cam elements are positioned to slide the sections of the blocks which provide bearings laterally and, at the same time, reciprocate the tamping bars vertically.

25 Each cam element of the camshafts is described from a different center whereby the tamping bars reciprocate individually and with the camshafts rotating at relatively high speed a beating action is obtained whereby the concrete is whipped into a plastic state.

30 The camshafts are actuated by a motor 21 secured to the upper plate 22 of a stand 23 by bolts 24 and a belt 25 trained over a pulley 26 on the motor shaft 27 provides means for rotating the camshafts by the motor.

35 The motor may also be connected to conventional driving means for propelling the tamping machine if desired.

With the motor turning at relatively high speeds such as 3600 r.p.m. the camshafts rotate at lower speeds, such as 4 to 1, by reduction resulting from the diameter of the small pulley 26, as compared to the diameter of the pulleys 28 and 29.

40 The speed ratio is only suggestive as it will be understood that pulleys may be provided of different sizes in order to obtain any speed desired.

45 The upper sections 17 of the split bearings are provided with an inverted V-shaped upper edge 30 that is positioned to slide in a correspondingly shaped groove 31 of the tamping bars or plates 10 and the lower sections 18 of the blocks are provided with V-shaped edges 32 that travel in similarly shaped slots or grooves 33 in the tamping bars. By this means the bearing blocks are secured in position laterally and remain in the slots 15 and 16 of the bars continuously.

50 The extended ends of the camshafts on which the pulleys 28 and 29 are positioned are also provided with sprockets 34 and 35 over which is a roller chain 36 is trained and the upper strand of the chain is positioned to engage an adjustable idler sprocket 37 mounted on the member 23 of the supporting structure whereby slack in the chain may be taken up.

55 The camshaft 14 is rotatably mounted by bearings 38 and 39 on the channel bars 11 and 12 and the shaft 13 is mounted by similar bearings 40 also positioned upon the upper flanges 41 of the channel bars.

60 The platform or plate 22 upon which the motor 21 is mounted is supported by a plate 23 at the outer end and also by a plate 42 at the opposite end and the base 43 of the motor is secured to the plate or platform 22 with bolts 44.

65 Rollers 45 and 46 extended by arms 47 and 48 from the leading end of the machine are rotatably mounted on a

haft 49. The tubular arms 47 and 48 are pivotally mounted on longitudinally disposed bars 50 by studs 51 having wing-nuts 52 thereon and the trailing ends of the arms are provided with studs 53 that extend into slots 54 in the member 50 providing means for raising and lowering the rollers 45 and 46.

The bars 50 are secured, such as by welding, to ends of the channel bars 11 and 12, and the bars 50 are mounted with the ends extended beyond the webs of the channel bars, as shown in Figures 1 and 5.

The rollers 55, at the rear for following the tamping bars are mounted in brackets 56 on lower surfaces of the handle 57 with caster-like yokes 58 whereby the device is readily maneuverable by a handle bar 59 at the upper end of the handle 57. The rollers are mounted in the yokes 58 which shafts 60.

The lower end of the handle 57 is secured to the beam 2 with a bearing bracket 61 and the lower end of the handle rests upon a transversely disposed plate or shoe 2 secured to a flange 63 on the lower end of the beam or channel bar 12.

A similar shoe 64 is secured to the lower flange 65 of the cross beam or channel bar 11 and the elevation of the hoses 62 and 64 is readily adjusted by adjusting the positions of the rollers 45 and 46. The arms of the yoke 58 are connected with a cross bar 66 as shown in Figures 3 and 5.

A tank 67 having a filling opening 68 is positioned on the handle 57 and, as shown in Figure 1, a tube 69 extends from the lower end of the tank, and provided with a valve 70, extends forwardly to the rollers 45 and 46 and the forward end is provided with a perforated section 71 that provides a water spray over the rollers 45 and 46 to prevent material adhering to the surfaces of the rollers. The tank 67 is secured to flanges 72 extended from the handle 57 and also to the trailing edge of the platform 22 upon which the motor 21 is mounted.

The tamping bars 10 are rectangularly shaped in elevation and the horizontally disposed slots 15 and 16 extend inwardly a distance at least equal to the lengths of the bearings plus twice the eccentricity of the cam surfaces, from end surfaces whereby the slots are positioned to receive the blocks having V-shaped upper and lower edges forming the bearings for the camshafts and the lower portions of the tamping bars are provided with extensions 73 and 74 which extend beyond the framework of the machine making it possible to tamp material up to all surfaces at the sides or ends of a floor or concrete slab.

Operation

With the parts assembled as illustrated and described the tamping device is positioned on bituminous concrete or the like and with the motor started the tamping bars are reciprocated by the camshafts whereby a high speed tamping action is obtained thoroughly tamping the concrete or other mixture and increasing the density or compactness thereof.

The machine may be provided with any suitable amount of tamping bars and the parts may be operated by an electrical motor as shown, or by a gasoline engine or other power means.

It will be understood that modifications, within the scope of the appended claims may be made in the design and arrangement of the parts without departing from the spirit of the invention.

What is claimed is:

1. A tamping machine comprising a horizontally disposed frame, horizontally positioned transversely disposed tamping bars having horizontally disposed slots extended inwardly from the ends, mounted in the frame, camshafts extended through the slots in the ends of the horizontally disposed bars, bearings positioned in the slots of the bars and in which cam elements of the camshafts are mounted, the lengths of the slots being at least equal to

the length of the bearings plus twice the eccentricity of the cam elements of the camshafts, said camshafts having cam elements corresponding in thickness with that of the bearings and bars, means for rotating the camshafts, and rollers upon which the frame is mounted.

2. A tamping machine comprising a horizontally disposed frame, transversely positioned tamping plates with slots extending inwardly at the ends and mounted to slide vertically in the frame, camshafts rotatably mounted in the frame, extended through the slots in the ends of the tamping plates, and having cam elements corresponding in thickness with that of the tamping plates, bearings mounted on the cam elements of the camshafts and positioned in the slots in the ends of the tamping plates, the length of the slots being at least equal to the lengths of the bearings plus twice the eccentricity of the cam elements of the camshafts, means carried by the frame for rotating the camshafts, and rollers mounted on the frame for supporting the frame and tamping bars.

3. A tamping machine comprising a horizontally disposed frame, transversely positioned tamping plates with slots extending inwardly at the ends mounted to slide vertically in the frame, camshafts rotatably mounted in the frame extended through the slots in the ends of the tamping plates, and having cam elements corresponding in thickness with that of the tamping plates, bearings mounted on cam elements of the camshafts and positioned in the slots in the ends of the tamping plates, the lengths of the slots in the ends of the tamping plates being at least equal to the lengths of the bearings plus twice the eccentricity of the cams, means carried by the frame for rotating the camshafts, rollers mounted on the frame for supporting the frame and tamping bars, and means for adjusting the positions of the rollers for controlling the elevation of the tamping bars.

4. A tamping machine comprising a horizontally disposed frame, transversely positioned tamping plates with slots extending inwardly at the ends mounted to slide vertically in the frame, camshafts rotatably mounted in the frame extended through the slots in the ends of the tamping plates and having cam elements corresponding in thickness with that of the tamping plates, bearings mounted on cam elements of the camshafts and positioned in the slots in the ends of the tamping plates, the slots in the ends of the tamping plates being horizontally positioned and the lengths of the slots being at least equal to the lengths of the bearings plus twice the eccentricity of the cam elements of the camshafts, means carried by the frame for rotating the camshafts, rollers mounted on the forward and rearward ends of the frame for supporting the frame and tamping bars and means for supplying water to said rollers at the forward end of the frame.

5. A tamping machine comprising a horizontally disposed frame, vertically disposed transversely positioned tamping plates with horizontally positioned slots extending inwardly at the ends mounted to slide vertically in the frame, camshafts rotatably mounted in the frame extending through the slots of the tamping plates, and having cam elements corresponding in thickness with that of the tamping plates, thereon, bearings mounted on the cam elements of the camshafts and positioned in the slots in the ends of the tamping plates, the lengths of the slots being equal to the lengths of the bearings plus twice the eccentricity of the cam elements of the camshafts, a motor carried by the frame, a belt trained over pulleys on the motor shaft and camshafts, for rotating the camshafts, and rollers mounted on the frame for supporting the frame and tamping bars.

6. In a tamping machine the combination which comprises a frame including transversely disposed channel bars positioned in spaced relation, tamping bars slidably mounted between the channel bars, the ends of the tamping bars having horizontally disposed slots extended inwardly and also having extensions extended outwardly from the lower edges thereof, camshafts having cam

elements corresponding in thickness with that of the tamping bars, extended through the slots in the ends of the tamping bars, rotatably mounted on the channel bars, bearing blocks mounted to slide longitudinally in the slots in the ends of the tamping bars and in which cam elements of the camshafts are positioned, the lengths of the slots in the ends of the tamping bars being equal to the lengths of the bearing blocks plus twice the eccentricity of the cam elements of the camshafts, supporting rollers mounted on the frame, means for adjusting the position of the rollers for adjusting the elevation of the frame, power means mounted on the frame and operatively connected to the camshafts for rotating the camshafts and means also mounted on the frame for supplying water to rollers extended from the leading end of the frame.

7. In a tamping machine the combination which comprises a frame including transversely disposed channel bars positioned in spaced relation, tamping bars slidably mounted between the channel bars, the ends of the tamping bars having horizontally disposed slots extended inwardly therein, camshafts having cam elements corresponding in thickness with that of the tamping bars, rotatably mounted on the channel bars, bearing blocks mounted to slide longitudinally in the slots in the ends of the tamping bars and in which cam elements of the camshafts are positioned, the lengths of the slots in the ends of the tamping bars being equal to the lengths of the bearing blocks plus twice the eccentricity of said cam elements of the camshafts, supporting rollers mounted on the frame, means for adjusting the position of

the rollers for adjusting the elevation of the frame, power means mounted on the frame and operatively connected to the camshafts, a handle extended upwardly from the frame, a water tank positioned on the handle, a perforated tube extended above rollers extended from the forward end of the frame and means for connecting the water tank to the perforated tubes.

5 8. A tamping machine comprising a horizontally disposed frame, spaced transversely disposed vertically positioned channel bars mounted in said frame, transversely positioned tamping plates having slots extended inwardly in ends thereof between the channel bars and positioned with side surfaces thereof in meeting and also in sliding relation, outer surfaces of the outermost tamping plates 10 also being in meeting and sliding relation with inner surfaces of the channel bars, camshafts rotatably mounted on the frame and positioned with cam elements thereof extended through the slots of the tamping plates, means for rotating the camshafts, means for supporting the frame in spaced relation to a surface upon which the machine is positioned, and means for adjusting the elevation of the tamping plate assembly.
